UNITED STATES PATENT OFFICE

2,599,273

WATER-POWERED ACTUATOR

John T. Mitchell, Memphis, Tenn.

Application October 20, 1947, Serial No. 780,808

3 Claims. (Cl. 253—2)

1

This invention relates to a water powered machine for mechanically actuating toilet implements such as tooth brushes which are conventionally operated by hand for mechanically performing the normal operation of the implement to thereby enable crippled or infirm persons to accomplish their toilet without assistance and to provide a machine adapted for general use to promote and insure proper utilization of the toilet implement.

More particularly, it is an object of the present invention to provide a water powered machine of extremely simple construction adapted especially to be utilized for actuating a tooth brush in the accomplishment of the cleansing of the teeth by a correct method and the use of which will discourage improper cleaning of the teeth.

Still a further object of the invention is to provide a machine of the afore-described character of extremely simple construction capable of being readily operated by the water power from a conventional household faucet and which may be conveniently applied to or removed from a wash bowl of a lavatory.

A further object of the invention is to generally improve the design efficiency and operation of means for utilizing water power and converting such power to the actuation of implements.

The means by which the foregoing and other objects of the invention are accomplished and the manner of their accomplishment will be readily understood from the accompanying specification upon reference to the accompanying drawings in which:

Fig. 1 is a side elevational view of the device;

Fig. 2 is a fragmentary top plan view thereof;

Fig. 3 is a longitudinal sectional view taken substantially along a plane as indicated by the lines III—III of Fig. 2;

Fig. 4 is a cross sectional view taken substantially along a plane as indicated by the lines IV—IV of Fig. 2;

Fig. 5 is a horizontal sectional view taken substantially along a plane as indicated by the lines V—V of Fig. 4;

Fig. 6 is an enlarged horizontal sectional view taken substantially along a plane as indicated by the lines VI—VI of Fig. 3;

Fig. 7 is an enlarged sectional view taken substantially along a plane as indicated by the lines VII—VII of Fig. 2;

Fig. 8 is a top plan view of a variation of the device;

Fig. 9 is a sectional view taken on the line IX—IX of Fig. 8;

2

Fig. 10 is a side elevational view of one side of the variation shown in Fig. 8;

Fig. 11 is a fragmentary sectional plan view taken on the line XI—XI of Fig. 10; and

Fig. 12 is a fragmentary side elevational view from the side of the device opposite Fig. 10.

Referring more particularly to the drawings, the numeral 10 designates generally the novel toilet implement actuator in its entirety and 10 which includes a housing or casing 11 which may be formed of a transparent or opaque plastic or any other suitable material and which includes a substantially cylindrical upper portion provided with a cover plate 12 and a restricted lower portion including a downwardly and inwardly inclined wall portion 13. The restricted lower portion of the housing 11 terminates at its bottom in a restricted outlet 14.

The inclined wall portion 13 is provided with 20 an internal boss 15 forming an upwardly opening thrust bearing for the unthreaded lower end of a threaded shaft 16 which is journaled in a bearing 17 formed in the cover 12. An impeller, designated generally 18, includes a hub 19 which 25 is threaded on the shaft 16, beneath and adjacent the bearing 17 and which is adjustably fixed thereto by nuts 20 which are threaded on said shaft, above and beneath the hub 19. The hub 19 is provided with a plurality of blades 21 which 30 project radially from the periphery thereof and which are provided with recessed outer end portions forming buckets 22 all of which face in the same direction, as clearly illustrated in Fig. 5. As seen in Fig. 5, the upper, substantially cylindrical portion of the housing 11 is provided 35 with a substantially straight portion 23, located above the inclined wall portion 13 and in which forms a nozzle 24 which opens into the upper part of the casing 11 in a direction generally tangentially thereof. The nozzle 24 is adapted 40 to be connected to one end of a hose or other flexible conduit 25 the opposite end of which connects in suitable manner to a source of water under pressure, such as a water faucet, not shown. The water under pressure from the source will be 45 conveyed through the conduit 25 to the nozzle 24 from which it will be ejected under pressure in a direction toward the inner or concave side of each of the buckets 22 as the impeller 18 is 50 revolved thereby and it will be readily apparent that the buckets 22 in moving into the path of the jet of water from the nozzle 24 will be impelled thereby for causing said impeller 18 to revolve in a counter-clockwise direction, as seen in Figure 5 for turning the shaft 16 in the same direction.

A hook 29 is preferably secured to the upper portion of the casing 11 substantially opposite to the nozzle 24 and is adapted to engage over the rim of a wash bowl or the like for supporting the actuator 10 thereon and so that the actuator may be readily demounted therefrom, when not in use. A drain hose 30 is attached to the outlet 14 for carrying off the water from the casing 11 to the drain or outlet, not shown, of the wash bowl or basin on which the actuator 10 is mounted.

The cover 12, as best seen in Fig. 3, is provided with a pair of opposed upstanding ears or projections 31 which are provided with aligned apertures for journaling unthreaded portions of a pair of screws or other journal elements 32 which project inwardly therethrough and which threadedly engage in end wall portions 33 of an elongated cradle 34 which is supported thereby to oscillate on its longitudinal axis and which includes outwardly bowed longitudinal side portions 35 which straddle the upper portion of the shaft 16 and the upper edges of which provide a support for a top surface or table 36 formed in sections, the adjacent ends of which are spaced from one another and are of concave shape to provide a central opening therebetween for readily accommodating the upper portion of the shaft 16. The sections forming the table or top 36 are tapered toward their remote ends and either or both of said sections is provided with a pair of longitudinally spaced strap members 37 for detachably engaging the handle end of a toilet implement which, in the embodiment of the invention as disclosed embodies a conventional tooth brush 38 which is supported thereby longitudinally of the cradle 34 and with the headed end thereof spaced outwardly therefrom and disposed with the bristles thereof projecting upwardly.

As best seen in Fig. 3, a disc 39 is detachably and adjustably fixed to the upper, threaded portion of the shaft 16 between retaining nuts 40 and is disposed obliquely to said shaft and within the cradle 34 and between the sides 35 thereof. As seen in Figures 4 and 6, the sides 35 are provided with inwardly projecting lugs 41 which are disposed beneath the disc 39 to be alternately engaged by the lower half thereof to cause the cradle 34 to rock or oscillate on its journals 32 when the shaft 16 is revolved for thereby oscillating the tooth brush 38 on its longitudinal axis.

A small rubber cup or brush 42, such as is employed by dentists for cleaning teeth of patients, having a shaft 43 carrying at its lower end nut 43A may be detachably mounted by threadedly engaging the upper end of the shaft 16 and above the cradle 34 to be utilized in addition to the tooth brush 38 for polishing the teeth after they have been cleaned by the bristles of the brush 38.

The hose 25, adjacent the nozzle 24 is provided with a branch conduit 44 which connects to one end of a small flexible tube or hose 45 the opposite end of which opens adjacent the under side of the head of the tooth brush 38 and is detachably applied thereto by extending through an apertured ear or lug 46 which projects from the under side of the shank of the brush 38. The hose 45 extends through a clamp 47 carried by the casing 11 and including a wing nut which may be manually tightened for compressing the tube 45 between the jaws or legs of the clamp 47 for shutting off the passage of water therethrough. The tube 45 is adapted to be employed for rinsing out the mouth after washing the teeth with a

tooth paste or powder and after the washing operation has been accomplished the clamp 47 is opened to allow water to flow through the tube 45 to be discharged into the mouth for rinsing out the mouth during the concluding strokes of the tooth brush.

It will be readily apparent that the rocking or oscillating motion of the cradle 34 will be imparted to the tooth brush 38 to cause the latter to oscillate or rock on its longitudinal axis thereby imparting thereto a motion corresponding to the recommended motion for manually actuating a tooth brush to correctly cleanse the teeth. By this motion, the head of the tooth brush 38, when positioned in the mouth, will be moved back and forth in a direction longitudinally of the teeth and transversely of the gums for fully cleaning between the teeth. It will also be readily apparent that the tooth brush may be inverted from its position of Figs. 2 and 3 and when so disposed may be efficiently utilized for cleaning the inner sides of the teeth on one side of the mouth and the outer sides of the teeth on the opposite side of the mouth.

In the variation illustrated in Figs. 8 to 12 inclusive, the device is shown as housed in a casing 111 which includes substantially identical top and bottom plates 112, 113 spaced apart and a preferably continuous side and end wall 114 attached along the edges of the plates 112, 113. The plates 112, 113 preferably are each formed with one end arcuate, the curve thereof being approximately a semi-circle, and with the opposite end tapered from the curved portion. The wall 114 spans the space between the plates and corresponds in plan to the plan of the plates to provide an arcuate substantially semi-circular end wall 114A and side wall portions 114B converging therefrom to terminate in an outlet 115. The unthreaded portion of a shaft 116 having a threaded end portion is journalled in bearings 117 formed in the upper and lower plates the lower plate being provided with a thrust member 113A covering the lower open end of the lower bearing 117 to form an upwardly opening thrust bearing for the lower end of the shaft 116, the upper end of which is threaded and projects above plate 112. The impeller of the variation is designated generally as 118 and includes a hub 119 which is keyed to shaft 116 between and abutting the inner ends of bearing 117. The hub 119 is provided with a plurality of blades 121 which project radially therefrom and which are provided with bucket like end portions 122, similar to the buckets 22 hereinbefore described, all of the buckets 122 being faced in the same rotational direction.

The arcuate end wall 114A is formed with an internally projecting nozzle 123 which is positioned to direct a stream of water toward the recesses of buckets 122 in a direction generally tangential of the path of rotation of the buckets. The nozzle 123 receives its supply of water from a conduit 124, connected in suitable fashion as by hose 125 to a source of water under pressure, not shown. The water under pressure will be conveyed through the hose 125 and conduit 124 to the nozzle 123 and therethrough against the buckets 122 to revolve the impeller 118 in the manner described for the impeller 18. A drain hose 130 may be attached to the outlet 115 for carrying off the water from the casing.

The upper plate 112 is provided with an upstanding ear or projection 131 which is apertured for journaling the unthreaded portion of a screw

or other journal element 132 which projects inwardly therethrough and threadedly engages in the end wall 133 of an elongated oscillatable member 134 which is turnably supported adjacent its opposite end in a collar 135 fixed to the upper plate 112 spaced from ear 131. The member 134 is provided with longitudinal slots 136, 136A, the slot 136 intersecting the slot 136A at right angles and the slots are respectively adapted to detachably engage the handle as of a tooth brush 137, thereby providing for operative attachment of the handle longitudinally of the member 134 in positions of choice, with the headed end outward from the actuator, the bristles projecting therefrom.

As shown in Figs. 9 and 12, a disc 139 is detachably secured to the upper threaded end of shaft 116 which projects above upper plate 112, by retaining nuts 140. The disc 139 is disposed obliquely to the shaft 116 and is provided with a peripheral groove 139A which is engaged by inwardly projecting lugs 141 carried by the arms of a yoke 142. The bight of the yoke is threadedly engaged and oscillatably supported by a screw or journal member 143, the unthreaded portion of which is journaled in an upstanding ear 144 fixed to the upper plate 112. It will be seen that as the obliquely disposed disc 139 is rotated by the revolution of the shaft 116, the lugs 141 are alternately raised and lowered by the peripheral disc groove 139A, to impart a rocking or oscillating motion to the yoke 142. One arm of the yoke is preferably provided with an extension 142A to which is pivotally secured one end of a link 145, the opposite end of which is pivotally secured to an ear 146 secured to the member 134. Through this linkage the yoke is operatively coupled to the oscillatable member and the rocking motion imparted to the yoke upon rotation of the disc is imparted therethrough to the oscillatable member 134, thereby oscillating the brush 137 on its longitudinal axis.

Preferably the conduit 124 adjacent but beyond the nozzle 123 is connected to one end of a flexible hose 147, the opposite end of which opens adjacent the side wall 114B or in other convenient position relative to the casing. The hose 147 extends through a clamp 148 which is secured to the wall 114, and which is adapted to be closed and shut off the passage of water through the hose and may be opened to supply rinse water as desired during cleansing of the teeth.

It will be seen that the oscillating motion imparted to the member 134 will by it be imparted to the brush 137 to rock it along its longitudinal axis in the desired tooth brush motion. It will also be seen that the intersecting slots 135, 136 provide for an adjusted brush position for each quadrant, so as to be more efficiently utilized in the cleaning of varying portions of the teeth and oral cavity.

It will be understood that the rinse water hose 45 or 147 may be dispensed with, in which case the branch conduit 44 is eliminated or the conduit 124 is closed by a suitable stopper member, not shown, beyond the opening of nozzle 123.

From the preceding description it will be readily apparent that other toilet implements including dry shavers, massaging implements, nail brushes or the like could be attached to the cradle 34 or to the yoke 142 and actuated thereby for accomplishing a personal hygiene or toilet operation normally accomplished by hand and where

an oscillating or reciprocating motion is normally applied to a toilet implement manually.

Various other modifications and changes are contemplated and may obviously be resorted to, without departing from the spirit or scope of the invention as hereinafter defined by the appended claims.

I claim:

- 10 1. A water powered actuating device comprising a housing, a water actuated rotary motor in said housing, means for supplying a jet of water to the housing for actuating said motor, a rotary shaft driven by said motor, head oscillatably mounted on said housing and means for oscillating said head which comprise a disc fixed to said shaft, concentric with said motor and at an oblique angle to the axis of said shaft, said disc having a peripheral groove, a pair of lugs diametrically opposed with respect to said disc and engaging said disc groove for alternate depression upon rotation of said shaft and means connecting said lugs to said head for rocking said head responsive to said alternate depression of said lugs.
- 20 2. A water powered actuating device comprising a housing, a water actuatable rotary motor in said housing, means for supplying actuating water to said motor, a rotary shaft driven by said motor, a head mounted on said housing for oscillation along its longitudinal axis, a disc concentrically fixed to said shaft exterior said housing at an oblique angle to the axis of said shaft, said disc having a peripheral groove, a yoke, a pair of lugs carried by the arms of said yoke, said yoke intermediate said arms and remote from said lugs being rockably attached to said housing, said lugs engaging said groove for alternate depression upon rotation of said disc to rock said yoke, and means coupling said yoke to said head whereby to impart the rocking imparted to said yoke to said head.
- 30 3. A water powered actuating device comprising a housing, a water actuated rotary motor contained therein, means for supplying a jet of water to the housing for actuating said motor, a rotary shaft driven by said motor, a head mounted on the exterior of said housing for rocking motion relative to said housing, a disc exterior of said housing fixed to said shaft concentrically with said motor and disposed at an oblique angle to the axis of the shaft, a yoke pivotally supported on said housing, and lugs diametrically opposed with respect to said disc and underlying the upper face of said disc carried by said yoke, said yoke being connected to said head and said lugs being engaged by said disc for alternate depression of said lugs when the shaft and disc are revolved, whereby to rock said head responsive to said shaft and disc revolution.

JOHN T. MITCHELL.
